UNITED STATES PATENT OFFICE.

SETH A. CRONE, OF NEW YORK, N. Y.

BRAKE-BEAM.

SPECIFICATION forming part of Letters Patent No. 731,668, dated June 23, 1903.

Application filed March 10, 1903. Serial No. 147,057. (No model.)

To all whom it may concern:

Be it known that I, SETH A. CRONE, a citizen of the United States, and a resident of New York, in the county of New York and State of New York, have invented certain new and useful Improvements in Brake-Beams, of which the following is a specification.

The invention relates to improvements in brake-beams for railway-cars; and it consists in the novel features of construction and combinations of parts hereinafter described, and particularly pointed out in the claims.

Brake-beams of the class to which my invention pertains comprise a rolled body-beam of suitable length, brake-heads of standard construction on the ends thereof, and a fulcrum for the brake-lever; and my invention has for its object to produce a novel fulcrum for use in such beams, said fulcrum being efficient and capable of being firmly and quickly applied to the beam.

The fulcrum of my invention may be formed of either one or two pieces of forged metal bent to the required shape and adapted to be firmly riveted or bolted to the body-beam.

My present invention pertains more especially to improvements in brake-beam fulcrums described and claimed in Letters Patent of the United States numbered, respectively, 720,676 and 720,677, granted to me on February 17, 1903; and its object is to produce a forged-metal fulcrum having its parts bent into the required shape, the parts of the fulcrum while being given such shape not being stretched or weakened, my invention contemplating the manufacture of the parts of the fulcrum without during the bending operations stretching or in any other manner weakening such parts.

The invention will be fully understood from the detailed description hereinafter presented, reference being had to the accompanying drawings, in which—

Figure 1 is an edge view of a fulcrum constructed in accordance with and embodying my invention, the fulcrum being shown as secured to a usual body-beam, the latter being in section on the dotted line 11 of Fig. 2. Fig. 2 is a side elevation, partly broken away, of a brake-beam equipped with a fulcrum embracing my invention. Fig. 3 is a detached top view of the fulcrum. Figs. 4 and 5 are

detached top views of the blanks from which the fulcrum parts are formed when said fulcrum is in two pieces, as shown in Figs. 1 and 2. Fig. 6 is a detached perspective view of the two main parts of the fulcrum as manufactured from the blanks shown in Figs. 4 and 5, and Fig. 7 is an elevation of the blank from which the fulcrum will be formed when the latter is in one integral piece instead of in the two separate parts represented in Fig. 6.

In the drawings I illustrate a brake-beam fulcrum formed of two parts and represent a blank from which a one-part forged-metal fulcrum may be formed, and in the Letters Patent of the United States No. 720,676 is shown a forged-metal fulcrum in one piece and in said Letters Patent No. 720,677 is shown a forged-metal fulcrum composed of two parts. The present invention in its broader scope therefore comprises a forged-metal fulcrum formed of either one or two parts, my invention being equally applicable to both characters of fulcrum, and comprising a new fulcrum structure in which the forged-metal parts thereof possess the maximum degree of strength and efficiency and in which said parts are not strained, stretched, or weakened in the bending processes incident to the manufacture of the fulcrum.

In the drawings, 10 designates a portion of the usual body-beam, and 11 the novel fulcrum of my invention, which is applied centrally on one edge of the beam, the latter preferably being of commercial shape. The fulcrum 11 may be formed of the two separate parts numbered 12 13, respectively, which when brought into proper relation to each other at the opposite sides of the beam 10 form the vertical sides 14 14, having at one end the flanges 15 16 17, while at the other end of said sides 14 are formed corresponding apertures 18 to receive the bolt upon which the usual brake-lever (not shown) will be mounted. The flanges 15, 16, and 17 at the inner end of the sides 14 respectively engage the sides of the web of the beam 10 and also the opposite sides and outer edges of the flange 19 of said beam, and the flanges 15 of said sides are provided with suitable apertures to receive the rivet or bolt 20 by which the fulcrum may be secured to the beam 10. The members 12 13 of the fulcrum may each be

formed from a blank or strip of forged metal, as shown in Figs. 4 and 5, Fig. 4 showing the blank 21, adapted for the formation of one member 12 of the fulcrum, and Fig. 5 illustrating a blank 22 for the formation of the other member of said fulcrum, and it is to be especially observed that each blank has an outer end portion 23 and that the portion 23 of one blank is reversely disposed to the portion 23 of the other blank, this being essential in carrying out the present invention and in enabling the manufacture of the fulcrum and the bending of the blanks into the required shape without straining or weakening the metal. The portions 23 of the blanks 21 22 are partly in line with the main body of said blanks, but are laterally disposed with relation thereto, leaving one edge 24 of the portion 23 extended laterally beyond the edge 25 of the body of the blank and the other edge 25 of the portion 23 set inwardly on a plane intermediate the parallel edges of the body of the blank. The edges 24 25 of the portion 23 of the blanks are connected by curved or inclined lines 26 with the main edges of the body of the blank.

The manner of forming the blanks of Figs. 4 and 5 into the fulcrum members 12 13 is clearly illustrated in Figs. 1, 2, and 6, in which it will be seen that the main part of the portion 23 of the blanks is fashioned into the flange 15, while those parts of the blank intermediate the curved lines 26 and adjacent thereto are fashioned into the flanges 16 and 17, the flange 16 resting against the inner surface of the flange 19 of the beam 10, whence the fulcrum member extends around the edge of said flange 19, and thence turns inwardly along and then outwardly on a diagonal line from the outer face of said flange 19, thereby forming the curved flange 17 and imparting to the side of the fulcrum member its desired angularity of position.

By manufacturing the fulcrum members 12 13 from blanks of the form shown in Figs. 4 and 5, having the laterally reversely offset end portions 23, the flanges 15, 16, and 17 may be formed without stretching or weakening the metal, and the said flanges 15 of said members may be arranged to set one a little in advance of the other on the beam 10, as shown by the solid and dotted lines, respectively, in Fig. 2, thereby leaving the opening between the sides 14 14 in proper condition to receive the brake-lever. (Not shown.) The formation of the fulcrum members 12 13 from the blanks 21 22 results in the curved portion 27 of the member 12 being projected laterally in one direction, as shown in Fig. 3, and the like portion 28 of the member 13 being projected laterally in the opposite direction, thereby increasing the strength and efficiency of the fulcrum members and permitting, without stretching the metal, the sides 14 14 to be given their proper angular position. It will be seen that the flange 17 at one edge, this being the lower edge looking at the left-hand

side of Fig. 3, is narrow and that from said edge the said flange 17 gradually broadens, and hence the broader edge of the flange 17, 70 this being the upper edge of said flange looking at the left-hand side of Fig. 3, extends to a considerable extent at the outer face of the flange 19 of the beam 10, and it is important in the formation of the flange 17 that in order 75 to give the latter its proper shape and size the metal be not stretched or unduly weakened. One purpose, therefore, of the special formation presented of the blanks 21 22 is to enable the formation of the flanges 17 and 80 the proper setting of the sides 14 without to any material degree stretching or weakening the forged-metal blanks. The fulcrum members produced from the blanks illustrated are of increased efficiency and the employment 85 of said blanks materially expedites the manufacture of the fulcrum members and in addition enables said members when formed to be conveniently given their proper positions 90 on the body-beam 10.

In Figs. 1 and 2 I illustrate the fulcrum made of two separate parts, and in the practical application of this fulcrum to the beam 10 it will be appropriate to connect the inner portions of the sides 14 by means of a bolt 95 or rivet 29 and to employ a separating-piece 30 on said bolt intermediate said sides, the latter being formed with apertures 31 to receive the said bolt or rivet 29. The sides 14 of the fulcrum (shown in Figs. 1 and 2) are 100 entirely open at their outer end.

While I illustrate in Fig. 1 a fulcrum formed of the two members 12 13 and made from the blanks shown in Figs. 4 and 5, I do not wish to limit the invention in every instance to a 105 two-part fulcrum, since many of the important features of the invention may be realized in the manufacture of a fulcrum in one piece, the fulcrum being then produced from a blank 32, (shown in Fig. 7,) which blank 110 corresponds exactly with the blanks shown in Figs. 4 and 5, except that it is in one integral piece and will be folded at its center, and thereby close the outer end of the fulcrum 115 shown in the aforesaid patent No. 720,676 is closed. The blank shown in Fig. 7 has the reversely-offset end portions 23 of the blanks shown in Figs. 4 and 5, and after the end portions of the blank shown in Fig. 7 have been 120 fashioned into the flanges 15, 16, and 17 the blank will be folded at its middle portion and then its sides will correspond exactly with the fulcrum members 12 13 of Fig. 1, with the exception that the sides of said members will 125 then be connected at their outer end by what was the middle portion of the blank 32.

What I claim as my invention, and desire to secure by Letters Patent, is—

1. The forged-metal brake-beam fulcrum 130 comprising the angularly-disposed side members having at their inner ends the flanges 15, 16 and 17, said side members having at their inner ends the laterally reversely offset end

portions 23 for the formation of said flanges; substantially as set forth.

2. The forged-metal brake-beam fulcrum comprising the angularly-disposed side members having at their inner ends the flanges 15, 16 and 17, said side members having at their inner ends the laterally reversely offset end portions 23 for the formation of said flanges, combined with means connecting said members adjacent to said flanges 17, and said members beyond said connecting means being apertured to receive the bolt for the brake-lever; substantially as set forth.

3. The forged-metal brake-beam fulcrum comprising the angularly-disposed side members having at their inner ends the flanges 15, 16 and 17, said side members having at their inner ends the laterally reversely offset end portions 23 for the formation of said flanges, combined with the bolt or rivet and separating-piece connecting and preserving the due relation of said members adjacent to said flanges 17, and said members beyond said separating-piece being apertured to receive the bolt for the brake-lever; substantially as set forth.

4. The forged-metal brake-beam fulcrum having the independent members 12, 13 open

at their outer end and comprising the angularly-disposed sides having at their inner ends 30 the flanges 15, 16 and 17, said members having at their inner ends the laterally reversely offset end portions for the formation of said flanges, and said sides being apertured to receive the bolt for the brake-lever; substantially 35

5. The forged-metal brake-beam fulcrum having the independent members 12, 13 open at their outer end and comprising the angularly-disposed sides having at their inner ends 40 the flanges 15, 16 and 17, said members having at their inner ends the laterally reversely offset end portions for the formation of said flanges, and said sides being apertured to receive the bolt for the brake-lever, combined 45 with means connecting said members adjacent to said flanges 17; substantially as set forth.

Signed at New York, in the county of New York and State of New York, this 7th day of 50 March, A. D. 1903.

SETH A. CRONE.
